Primary Examiner — Darlington Ly(74) *Attorney, Agent, or Firm* — Stetina Brunda Garred and Brucker(57) **CLAIM**

The ornamental design for a front vehicle bumper, as shown and described.

DESCRIPTION

FIG. 1 is a front perspective view of a front vehicle bumper showing my new design;

FIG. 2 is a top plan view thereof;

FIG. 3 is a left side elevation view thereof;

FIG. 4 is a right side elevation view thereof; and,

FIG. 5 is a front elevational view thereof.

The broken lines in the drawings illustrate portions of the front vehicle bumper that does not form part of the claimed design.
